SPLIT DUSTER ATTACHMENT FOR VACUUM CLEANERS

Vivian M. Wright, 6813 Timmons Drive,
Des Moines, Iowa 50322

Filed Apr. 10, 1968, Ser. No. 11,397

Term of patent 14 years

(Cl. D49—19)

Fig. 1

Fig. 4

Fig. 5

Fig. 2

FIG. 1 is a top perspective view of the attachment;
FIG. 2 is a top view of the attachment, the bottom view being the same in appearance.

FIG. 3 is a side elevational view of the attachment;
FIG. 4 is a front view of the attachment; and
FIG. 5 is a back view of the attachment.

I claim:

The ornamental design for a split duster attachment for vacuum cleaners, substantially as described and shown.
